(57) **CLAIM**

The ornamental design for a reusable silicon pad, as shown and described.

DESCRIPTION

FIG. 1 is a front-top-right perspective view of a reusable silicon pad showing my new design;

FIG. 2 is a rear-bottom-left perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left-side view thereof; and,

FIG. 8 is a right-side view thereof.
